UNITED STATES PATENT OFFICE

HAROLD G. WARR, OF PARK RIDGE, ILLINOIS, ASSIGNOR TO THE P & M COMPANY, OF CHICAGO, ILLINOIS, A CORPORATION OF ILLINOIS

RAIL ANCHOR

Application filed June 13, 1929. Serial No. 370,608.

My invention relates to rail anchors adapted to embrace the base portion of railroad rails and bear against the stationary part of a road-bed to resist longitudinal movement of the rail.

One of the principal objects of the invention is to provide a rail anchor adapted to grip one flange of a rail base by movement of a locking end portion into locking engagement with the other flange of the rail base, the latter portion of the anchor being provided with capacity for vertical movement relative to the rail without danger of disengaging the locking means.

Another object is to provide an anchor of the above character in which the locking end thereof is provided with a series of shoulders, one of which provides a locking engagement with the rail and another of

which provides a clearance between the edge of the rail base flange engaged and a part of the locking end of the device, whereby the locking end may have vertical sliding action relative to the edge of the base flange.

In this connection I contemplate also a locking end which may be flexed outwardly from the rail base during its application to the rail to permit one or more of the said locking shoulders to ratchet over a corner portion of the base flange and thereby lock the anchor against accidental disengagement.

Another and more specific object is to provide in combination with a downwardly curved body portion, a locking end adapted to be flexed outwardly into locking engagement with the rail base and to provide also a clearance shoulder adjacent the surface for bearing against the vertical edge portion of the rail, whereby the downwardly curved

portion of the anchor is held out of engagement with the adjacent edge of the rail base during any vertical movement of the anchor, for example, when the downwardly curved portion is pressed against the ballast

of the road-bed. In this connection I contemplate also the provision of a bearing surface of relatively large area for bearing against the vertical edge portion of the rail base, which exerts a spring grip transversely of the rail, in addition to the vertical grip

produced by the vertical movement of the anchor to its applied position.

A further and more specific object is to provide a rail anchor of the above general character having a jaw portion adapted to be moved into clamping engagement with the top and bottom surfaces of one base flange of a rail, by vertical movement of the other end of the anchor, and in which the said other end is flexed outwardly from the edge of the rail base during its application to a rail and is provided with a series of rail base engaging notches adapted to accommodate the anchor device to rail bases of different sizes.

Other objects of the invention will appear from a detailed description of the embodiments shown in the accompanying drawings.

In the drawings:

Fig. 1 is a plan view of a rail anchor constructed in accordance with my invention applied to the base flange of a railroad rail in position to bear against a vertical face of an adjacent cross tie.

Fig. 2 is a side view of the rail anchor shown in Fig. 1, the base flange of the rail being shown in section.

Fig. 3 is a view similar to Fig. 2, showing the anchor in one position which it assumes during its application to a rail.

Fig. 4 shows the same anchor as illustrated in Fig. 2 applied to a rail, the base portion of which is of a different size from that illustrated in Fig. 2.

Fig. 5 illustrates another form of the invention adapted to be applied to rail bases of different sizes, and

Fig. 6 is a view of the modified construction illustrating the manner in which it is applied to a rail.

Referring first to Figs. 1 to 3 inclusive of the drawings, 10 designates the base portion of a railroad rail and 11 is one of the cross ties on which the rail is supported. The rail anchor shown in these figures of the drawings consists of a spring metal bar, the body portion 12 of which extends across beneath the rail base in a position to bear against the cross tie. One end of the bar is

formed with a hook 13, the portions 14 and 15 of which provide upper and lower jaws which embrace the marginal portion of one base flange of the rail. Preferably, the opening of the hook 13 is somewhat greater than the thickness of the rail base flange which it embraces, and the bearings 14a—15a are moved into gripping engagement with the top and bottom surfaces of the rail base 5 by a clockwise turning movement of the jaw, as viewed in Figs. 2 and 3. The said gripping action of the jaws is produced by swinging the other end 16 of the bar upwardly from the position shown in Fig. 3 to 10 the position shown in Fig. 2. The under rail portion 12 of the bar is preferably bowed downwardly to provide a tie abutting portion which will bear against the cross tie at a substantial distance below the bottom of 15 the rail base and to also provide the end 16 with sufficient resilience to permit it to be readily flexed outwardly relative to the edge of the rail during the upward swinging movement of the bar. Preferably, the end 20 portion 16 is so disposed to the hook 13 that it is necessary to flex the end outwardly relative to the rail base to engage the said end over the base flange 18 of the rail. Consequently, when the end 16 is engaged with 25 the vertical edge of the base flange 18 of the rail, a spring grip is exerted transversely of the rail in addition to the grip exerted by the jaws 14 and 15 on the top and bottom surfaces of the rail. The outward flexing of 30 the end 16 is effected by a cam surface 16a, which slides over the edge of the rail base during the upward swinging movement of the bar.

In order to hold the anchor locked in its 35 applied position, the end 16 is provided with a series of shoulders 19, 20 and 21, one or more of which ratchets over and engages the marginal upper surface of the base flange 18 during the upward swinging movement 40 of the body. The size of the rail base to which the anchor is applied determines which of the said shoulders engages the upper corner of the base when the anchor is in its fully applied position. When the anchor 45 is applied to a rail base flange of the width and thickness shown in Figs. 2 and 3, the anchor will be sufficiently tight on the said base when the shoulder 19 snaps over the upper corner of the base. In such event the shoulder 20 provides a clearance between the 50 flexible end portion 16 of the anchor and the vertical edge of the rail. It will be observed that with the clearance provided by the shoulder 20, the end 16 may be moved a substantial distance upwardly from the applied position, shown in Fig. 2, without causing the curved surface 22 of the body to come into contact with the lower corner 23 of the rail base and thereby avoid outward 55 flexing of said shoulder relative to the upper

corner of the rail base when the body of the anchor is pressed down upon the ballast of the road bed.

The series of shoulders 19, 20 and 21 make it practicable to apply the anchor, herein shown, to base flanges of different sizes and at the same time permit upward movement of the end 16 relative to the rail base without outward flexing thereof when the bowed portion 12 is pressed downwardly on the ballast of the road bed.

In Fig. 4 I have shown the anchor of Fig. 2 applied to a rail base 24, which is somewhat wider and thinner than the rail base shown in Fig. 2. In this application of the anchor the end 16 must be raised somewhat higher than shown in Fig. 2, to produce the desired grip of the jaws 14 and 15 on the base flange 25. The proportions of the anchor are such that the shoulder 20 snaps over the upper edge of the rail base to lock the anchor in its rail gripping position, and the shoulder 21 provides clearance between the adjacent edge of the base flange of the rail to avoid contact of the curved surface 22 of the anchor with the lower corner 26 of the rail base, in a manner previously described.

The series of shoulders 19, 20 and 21 are so positioned in the drawings as to provide relative wide bearing surfaces 27 and 28 for engagement with the vertical edge surface of the rail. The width of these surfaces and likewise the number of shoulders employed may be varied to suit the conditions under which the anchor may be used.

In Figs. 5 and 6 I have shown a modified form of rail anchor adapted for engagement with rails having base flanges of different sizes. In this embodiment of the invention the spring end of the anchor is flexed outwardly relative to the edge of the rail base by forcing the said spring ends downwardly, instead of upwardly, as previously described. The embodiment shown in Figs. 5 and 6 consists preferably of an under rail portion 29, formed at one end with a hook 30, providing upper and lower jaws 31 and 32, respectively, for engagement with the top and bottom surfaces of one base flange of a rail. The other end of the bar is bent upwardly to provide a resilient upstanding arm 33, which is provided at its upper end with a series of notches 34, 35, for engagement with different sized base flanges. The inner face 36 of the arm 33 is inclined relative to the vertical edge of the rail base and functions as a cam to force the arm 33 outwardly relative to the edge of the rail base when the said arm is pressed downwardly across the base flange. The portion of the arm intervening between the notches 34 and 35 is provided with a cam surface 36a which rides over the edge of the rail base when the anchor is applied.

to a rail of the size indicated in the dotted lines in Fig. 5.

In applying this modified type of rail anchor to the base flange of a rail, the long arm 33 is first hooked over one flange of the rail base and the bar moved transversely thereof, until the jaw 31 clears the opposite edge of the rail base. At this point of the application, the jaw 31 can be moved over the adjacent edge of the rail base so as to embrace it in a manner indicated in Fig. 5, whereupon the resilient arm 33 may be pressed downwardly across the edge of the rail base and caused, by reason of the engagement of the cam surface 36, to be flexed outwardly relative to the rail base until one of the notches 34 or 35, as the case may be, snaps into engagement with the rail base flange to which the anchor is applied. When the anchor is in its applied position, the jaws 31 and 32 grip one flange of the rail base by reason of a rotary action to which they are subjected during the downward pressing of the arm 33. The downward flexing of the arm 33, together with the bearing of the hook 30 against the opposite edge of the rail base exerts a transverse spring grip.

I claim:

- 30 1. A rail anchor comprising an under rail portion provided with means for gripping one flange of a rail base and with a resilient locking portion adapted to be flexed transversely of the rail into locking engagement with the other flange of the rail base; said locking portion being formed with a series of shoulders, one of which projects over the upper corner of the base flange engaged, when the anchor is in its normally applied position, and another of which provides clearance between the adjacent edge of the rail base and said locking portion during upward movement thereof relative to its normally applied position.
- 45 2. A rail anchor comprising an under rail portion provided at one end with means for gripping one flange of a rail base and with a resilient locking portion adapted to be sprung outwardly from the rail into clamping engagement with the other flange of said base; said locking portion being formed with a series of shoulders, one of which projects over the upper corner of the base flange engaged, when the anchor is in its normally applied position, and another of which provides clearance between the adjacent edge of the rail base and said locking portion during upward movement thereof relative to its normally applied position.
- 55 3. A rail anchor comprising a downwardly bowed under-rail portion provided at one end with means for gripping one flange of a rail base and at the other end with a resilient locking portion adapted to be sprung outwardly from the rail into clamping en-

gagement with the other flange of said base; said locking portion being provided with a series of shoulders, one of which projects over the upper corner of the base flange engaged, when the anchor is in its normally applied position, and another of which provides clearance between the lower corner of the base flange engaged and that portion of the downwardly bowed under-rail portion adjacent said lower corner of the rail base, whereby the said locking portion of the anchor may be moved vertically of the rail without moving said bowed portion into contact with the edge of the rail base.

4. A rail anchor comprising an under rail portion provided at one end with a hook portion for gripping the top and bottom surfaces of one flange of a rail base and provided at the other end with a resilient locking portion adapted to be sprung outwardly from the rail into clamping engagement with the vertical edge thereof; said locking portion being formed with a series of shoulders, one of which projects over the upper surface of the last mentioned flange of the rail base, when the anchor is in its normally applied position, and another of which provides clearance between the lower edge of said base flange and the said adjacent part of said locking portion.

5. A rail anchor comprising an under rail portion provided with means adapted on vertical movement of the under rail portion to clamp the base, one end of said under rail portion being formed with a series of locking shoulders for engagement over the upper corner of a rail base flange and with a series of flat bearing surfaces for bearing against the vertical edge surface of said base flange and adapted to be flexed outwardly during said vertical movement to engage said shoulders successively with said corner portion of said base.

6. A rail anchor comprising an under rail portion provided with means adapted on upward movement of the under rail portion to clamp the base, one end of said under rail portion being formed with a series of locking shoulders for engagement over the upper corner of a rail base flange and with a series of flat bearing surfaces for bearing against the vertical edge surface of said base flange and adapted to be flexed outwardly during said vertical movement to engage said shoulders successively with said corner portion of said base.

7. A rail anchor comprising an under rail portion provided at one end with a hook shaped jaw adapted on vertical movement of the under rail portion to clamp the base flange of the rail, the other end of said under rail portion being provided with a series of locking shoulders for engagement over the upper corner of a rail base flange and a series of flat bearing surfaces for en-

- gagement with the vertical edge surface of said flange and adapted to be flexed outwardly during said vertical movement to engage said shoulders successively with said corner portion of said base.
8. A rail anchor comprising an under rail portion provided at one end with a hook shaped jaw adapted on upward movement of the under rail portion to clamp the base flange of the rail, the other end of said under rail portion being provided with a series of locking shoulders for engagement over the upper corner of a rail base flange and a series of flat bearing surfaces for engagement with the vertical edge surface of said flange and adapted to be flexed outwardly during said upward movement to engage said shoulders successively with the upper corner portion of said base.
- 20 9. A rail anchor comprising a yoke bowed downwardly relative to the rail and formed at one end with means adapted on upward movement of the other end to clamp one base flange and provided at said other end with a series of shoulders, one of which engages over the upper edge of the said other base flange and another of which provides clearance between the said other base flange and an adjacent portion of the yoke, and a cam surface adapted to press against the rail base to flex the shoulder end of the yoke outwardly relative to the rail during the applying movement of the anchor.
- 30 10. A rail anchor comprising an under rail portion provided at one end with means for gripping the top and bottom surfaces of one base flange of a rail base and formed at the other end with means engaging the marginal upper portion of the other base flange to hold said gripping means turned about an axis extending longitudinally of the rail, the under rail portion of the anchor being bowed downwardly to provide a tie abutment, the outer portion of said bowed part of the anchor being substantially parallel to the vertical edge of the rail base, whereby the said locking end of the anchor may be moved vertically from its applied position without pressing the curved inner surface of said bowed portion against the bottom surface of the rail base.
- 40 11. A rail anchor comprising an under rail portion provided at one end with means movable into gripping engagement with the top and bottom surface of the rail base by upward swinging movement of the other end of the anchor and provided at said other end of the anchor with a cam surface adapted to flex said end outwardly relative to the other base flange of the rail during said upward movement and provided with a shoulder for engagement with the marginal upper surface of the base flange to hold the first mentioned gripping means in gripping engagement with the rail base and provided
- also with an offset portion providing a clearance between a portion of the rail base and the outwardly flexible end portion of the anchor.
12. A rail anchor comprising an under rail portion formed at one end with means for gripping the top and bottom surfaces of one flange of a rail base and formed at the other end with a resilient locking tail adapted to be flexed outwardly into engagement with the rail base, said tail being formed with a series of notches, one of which provides a shoulder for engaging over the upper corner of the rail base and provides also a vertical surface for bearing against the vertical edge of the last mentioned flange, and another of said notches being formed at the lower end of said vertical bearing surface, whereby clearance is provided between the said vertical surface of the rail base and an adjacent portion of the anchor.
13. A rail anchor comprising an under rail portion provided at one end with a hook portion for gripping the top and bottom surfaces of one flange of a rail base and provided at the other end with a resilient locking portion adapted to be sprung outwardly from the rail into clamping engagement with the edge portion thereof; said locking portion being provided with a series of notches providing shoulders for engagement over the upper longitudinal corner of the last mentioned flange of the rail when the anchor is in its applied position, said shoulders being spaced apart a distance less than the thickness of the rail base flange at the point engaged.
14. A rail anchor comprising an under rail portion provided at one end with means adapted on downward movement of the other end of said under rail portion to clamp the base; the last mentioned end of the under rail portion being formed with a series of locking shoulders adapted to snap over the edge portion of the rail base to lock the anchor on the rail.
15. A rail anchor comprising an under rail portion provided at one end with means for gripping the marginal portion of one base flange upon the downward movement of the other end of said under rail portion, said last named end portion being provided with a series of notches for locking engagement with the other base flange of the rail and a cam surface intervening between said notches.
16. A rail anchor comprising an under rail portion provided at one end with a hook portion for clamping engagement with the marginal portion of one base flange of a rail and at the other end with a series of notches providing rail base engaging surfaces adapted, on downward movement of the last mentioned end portion of the anchor, to suc-

cessively engage the edge portion of the other base flange of the rail to maintain said hook in its rail clamping engagement, the distance between the rail engaging portions of the opposite ends of said anchor being such that the notched end portion is flexed outwardly from the rail base in forcing the anchor to its applied position.
